 American Viscose Corporation, Wilmington,
 Del., a corporation of Delaware

Application October 1, 1948, Serial No. 52,228

12 Claims. (Cl. 57—78)

1

This invention relates to an apparatus for stopping resiliently supported rapidly rotating mechanisms and particularly to a device which effects emergency stopping of textile twisting or winding machines.

The invention will be described with reference to a two-for-one strand twisting machine of conventional design since this machine typifies apparatus comprising portions which are self-propelled at high rotative speeds relative to a housing or bearing member. Such a member is ordinarily supported on resilient pads or spring devices which permit cushioning or absorption of vibration or other movement of the assembly comprising the member and the rotatable parts. The resilient support is such that the assembly may undergo universal movement or oscillation with respect to the axis of the machine. The rotor of a two-for-one twisting machine of standard construction includes a driving motor armature, the shaft of which is extended to support a flyer secured thereto and rotatable therewith, and a package holder supported thereon by anti-friction bearings so that it may be held stationary. The rotor speeds of this machine are normally in the range of 6000 to 10,000 revolutions per minute. Machines of this type are subject to an occasional interruption in operation resulting from a mechanical failure such as bearing seizure or tangling or snarling of the strand as it is drawn from the package. The package holder and the package supported thereon is prevented from turning so that two twists are put into the yarn for every revolution of the rotor. One satisfactory arrangement for preventing rotation of the package holder consists of magnets attached to a nonrotating part of the machine which act on steel elements of the package holder. No particular care is taken in the construction of the package holder or in the placement of the package thereon to obtain dynamic balance about the rotor axis. Hence, if on account of an irregularity in the operation of the machine, such as seizure of the holder bearings, the holder and the package start rotating, slight unbalance in the rotor and package cause the rotor assembly and housing therefor to oscillate or otherwise move on the resilient supporting means. Movements of minor amplitude such as produced during normal operating conditions or stopping and starting are readily absorbed by the resilient supports or mountings and effectively reduce the wear and maintenance on the machine. However, the mountings do not provide protection against some of the more serious difficulties

2

which may occur, such as a bearing seizure, except insofar as they permit unusual movement or vibration of resiliently supported parts, indicating to an observer improper operation of the machine.

It is an object therefore to provide stopping means for winding or twisting machinery typified by the two-for-one strand twister wherein a rotor assembly is supported in means capable of oscillatory movement normal to the rotor axis in response to unbalanced rotational forces. It is another object to provide emergency stopping means for machinery comprising a resiliently supported high speed rotor, operable in the event of mechanical failure. Still another object is to provide deceleration means for a resiliently supported rotor while eliminating the necessity for mechanical brakes and the like. It is a further object to provide a greatly simplified and easily maintained mechanism for effecting routine and emergency stopping of individual machines such as found in batteries or groups of textile winding and twisting machines. Other objects, features and advantages will become apparent in the following description of the invention and the drawing relating thereto in which

Fig. 1 is an elevation view partly in section along the rotor axis of a two-for-one twisting machine containing an embodiment of the invention;

Fig. 2 is a section view along line II—II of Fig. 1;

Fig. 3 diagrammatically illustrates an electrical circuit for interrupting the flow of power to a rotor driving means;

Fig. 4 illustrates another electrical circuit employing a double-pole double-throw switch adapted for reversing the current to the drive means during deceleration thereof;

Fig. 5 illustrates a modification of the circuit illustrated in Fig. 2 containing a time delay relay switch;

Fig. 6 is a further modification of the circuit illustrated in Fig. 3 incorporating a double-pole centrifugal switch operated by the rotating element of the driving means;

Fig. 7 is a top view of a unit containing four microswitches with the top cover removed;

Fig. 8 is a section of the unit taken along line VIII—VIII of Fig. 7; and

Fig. 9 is a circuit diagram including the unit illustrated in Figs. 7 and 8 for controlling the electrical power to the driving means for the rotor.

In brief, the invention comprises automatic means for stopping a mechanism contained within a resiliently supported or suspended housing. The automatic means is an electrical circuit controlling device operated by contact with the housing when it vibrates or performs movement of unusual amplitude in response to improper operation of the mechanism. In the various modifications of the automatic means illustrated, electrical power for driving the mechanism may be controlled to permit coasting of the mechanism to a dead stop or to produce rapid deceleration effects such as by reversal of the current during a portion or all of the deceleration period.

In Fig. 1 of the drawing, a two-for-one twisting machine, illustrated in a partially sectioned elevation view, comprises an electrical motor 11 and a spindle shaft 12 supported on and in alignment with the motor shaft. The spindle shaft 12 supports a rotatable package support 18 (prevented from rotating by means such as magnetic or gravity means hereinafter described) and a rotatable flyer 16 secured to the shaft. The entire assembly comprising the motor 11, package holder 18, and flyer 16 is resiliently supported upon the machine frame member 18 by a plurality of resilient supporting devices 19. The package holder 18 is prevented from turning by electromagnets 14 secured to the motor housing acting upon iron or steel cleats 17 secured within the lower surface of the package holder.

The supports 18 may be of any of the many types used to absorb vibrations while supporting machinery of vibration-producing tendencies such as high speed rotary mechanisms. A force such as from a vibration applied to a support 18 through the pin 20 from any direction whatsoever will be resisted and absorbed within the resilient elements 23 and 24 of the assembly constituting the support 18. These supports comprise an outer rigid sleeve 22, annular resilient or rubber-like members 23 and 24 preferably secured at either end of the sleeve 22, and pins 20 and 27 extending through sleeves 29 and 30 secured within the rubber-like members 23 and 24 respectively. The pin 20 extends through an aperture therefor through the plate 34; a collar 25 is secured to the pin. The pin 27 extends through an aperture in the frame 18 and is provided with a collar 26 similarly to pin 20.

Fig. 2 shows a top view of the plate 34 of generally circular contour except for the straight section 35 of its periphery which permits closer positioning toward the axis of rotation of the machine of a switch unit 100 including a button-pushing lever 107 to effect compactness.

Fig. 3 is a circuit diagram wherein the power shown supplied through lines 40 and 41 connected to a double-pole single-throw trip switch 44. Line 42 is connected with one phase of the electrical driving motor 11. The switch is tripped open when the button 47 is engaged by the plate 34 during excessive vibration or wobbling of the twisting machine. The switch may be reset or the circuit closed by pushing the reset button 48. When using this type of control, a driving motor such as the motor 11 coasts to a stop. Although the arrangement illustrated in Fig. 3 is the most simplified type of circuit control to be herein described, on account of the vibration that may occur over a considerable time interval while the mechanism is coming to a stop, the modifications to be hereinafter described may be preferred.

By using a double-pole double-throw switching arrangement current may be reversed in two of

the three phases of a driving motor to reverse the rotation of the motor to obtain a greatly shortened deceleration period for the machine.

In the control system illustrated in Fig. 4, two of the three phases carried in lines 40, 41 and 42 are connected to the movable terminals 53 and 55 of the double-pole double-throw switch. Line 42 is connected directly with the remaining terminal of the motor 11. The terminals 53 and 55 normally assume an intermediate position between 2 sets of stationary terminals of the switch by reason of their being mounted on a spring member 50. In normal operation of the motor, the terminals 53 and 55 are in contact with the stationary terminals 51 and 52 to maintain two lines of the normal operating circuit of the motor 11. The movable terminals are held in contact with terminals 51 and 52 by the influence of a magnet 54 on an armature 60 attached to the spring member 50. In the position of the movable terminals intermediate of the two sets of stationary terminals, the armature 60 is out of the influence of the magnet 54. Thus when the motor 11 vibrates sufficiently, the portion 34 thereof engages the push buttons 56 secured to the spring member 50. The movable terminals 55 are moved out of contact with terminals 51 and 52 and into contact with the other set of stationary terminals 58 and 59. Terminals 58 and 59 are connected with the motor terminals which are also supplied by and connected with terminals 51 and 52 but in a manner such as to reverse the flow of the current and to cause the motor to rapidly decelerate when the spring member 50 is deflected by the motor member 34. When the motor has been slowed to a speed at which the vibration subsides to the extent that the motor portion 34 no longer touches or engages the push button 56, the lever 50 carries the terminals 53 and 55 out of contact with terminals 58 and 59 into their normal position intermediate of the two sets of stationary terminals and the motor 11 and connected rotative parts coast to a stop.

Fig. 5 illustrates a variation in the arrangement shown in Fig. 4 by which a time delay relay switch has been incorporated into the electrical control system to effect complete stoppage of the motor 11. By this arrangement, portion 34 of the machine moves the button or lever portion 62 of switch 63 out of contact with the terminals 65 and 66, and into contact with the terminals 68 and 69. Thus the flow of current is discontinued to two phases of the motor 11 through the terminals 65 and 66. When the switch makes contact with the terminals 68 and 69 the current is reversed with respect to the phases of the motor and the motor is rapidly decelerated. However, in this position of the switch another circuit is closed through the terminal 69 which energizes the coil 71 of the relay switch 70. The delay relay coil 71 is adjusted to hold the reverse current on the motor for an interval which is indicated by experience to be necessary to nearly stop the machine and then it opens the circuits to the motor. The coil 71 operates the switch 73 and breaks the motor circuits at terminals 74 and 75. The machine is again put into operation by closing the switch 63 with respect to the terminals 65 and 66 by a reset button 77. As applied to the two-for-one twister which is shown in Fig. 1, the relay 70 is sometimes adjusted to allow time for the flyer 16 to reach substantially full speed in a direction opposite to its normal direction before it shuts off the current to the motor. This rapid reverse rotation stabilizes the assembly while the

package support 15 is coasting to a stop. This adjustment is generally used when accidental rotation of the package support by the operator, or rotation due to partial seizure of the bearings 121 and 122 is more probable than rotation due to complete and sudden seizure of these bearings. A snap action double-throw switch of conventional design may be used with the arrangement of Fig. 5 to provide fast and precise operation.

Fig. 6 illustrates a circuit arrangement in which a double-pole double-throw switch construction similar to switch 63 of Fig. 5 is used to obtain reversal of current through 2 phases of the motor 11. However if the circuit is broken with respect to terminals 82 and 83 and closed with respect to terminals 85 and 86, current passes through a conventional double-pole centrifugal switch 88 having terminals 90 and 91 and mounted on the motor and then through the phases of the motor in the reverse direction. As a result the rotor of the motor is decelerated rapidly until the switch is no longer held closed by centrifugal force at terminals 90 and 91 against springs 95 and 94 which urge the switch to an open position; with the flow of power thus terminated, the motor 11 coasts to a stop. The centrifugal switch 88 may be adjusted to open the motor circuit at any speed desired; preferably it is adjusted to cut out at very slow speeds of the motor. The machine may thereafter be put into operation by resetting the switch 88 by means of a reset button 96.

Figs. 7, 8, and 9 show a group of four microswitches set in a single unit, the top view being shown in Fig. 7 and an end view being shown in Fig. 8. Fig. 9 illustrates the circuit arrangement for these switches. It will be recognized that this is essentially similar to the circuit arrangement which is shown in Fig. 4. In the unit 100 as shown in Fig. 7, switches 102 and 103 are closed when buttons 105 and 106 are contacted by a lever 107 normally held away from the buttons by a spring 119 when the lever is not deflected by the motor part 34. The lever is secured by its lower end as viewed in Fig. 8 to the wall 108. A small spacer element 124 such as a rivet through the lever 107 holds the lever away from the inner surface of the wall of the unit 100. Switches 110 and 111 are opened when buttons 113 and 114 are pushed by the lever 107. Switches 110 and 111 are of the reset type and both switches may be simultaneously reset by pushing button 116 which engages the small buttons 117 and 118.

The lever 107, which engages all four buttons of the switches in the unit, is so shaped that the buttons 113 and 114 are engaged before buttons 105 and 106 during deflection of the lever 107. Because switches 110 and 111 control the motor circuits in normal operation of the machine, it is desired to break these circuits before closing the current-reversing circuit controlled by switches 102 and 103 to avoid all possibility of a short circuit. To obtain this result, the side margins of the lever 107 which engage the buttons of the outer surfaces may be bent away from the plane of the surface of the lever which contacts the buttons 113 and 114 of the inner switches. In the circuit diagram in Fig. 9 it will be seen that as the lever 107 is moved inwardly toward the buttons of the switches, the circuits connecting two of the power lines 40 and 41 with two phases of the motor 11 and carried by switches 110 and 111 are first opened and the buttons of switches 103 and 102 are then engaged to reverse the motor circuits which nor-

mally pass through switches 110 and 111. The microswitches just described may be operated also in conjunction with such devices as the delay relay switch described with respect to Fig. 5, or the centrifugal switch referred to when describing the circuit of Fig. 6. In Fig. 9, a solenoid 120, shown connected to lines 121 and 122, is included to operate a signal to indicate stoppage of the machine or to stop auxiliary equipment such as a take-up means operated in conjunction with the twisting device. If desired, the solenoid or similarly connected device may be omitted.

The proximity of the switch operating means in relation to the twisting machine housing, i. e., the resiliently supported portion of the machine, will be determined by experiment since it is dependent upon the amplitude of the vibration of movement made by the resiliently supported portion during ordinary operation including starting and stopping of the machine. The switches will be set at sufficient clearance with respect to the member 34 of the machine to be operated by contact resulting from vibration and movement greater than a predetermined amplitude.

The invention herein described may be used instead of various mechanical and electrical brake setting mechanisms now in use for the emergency stopping of textile winding and twisting machines by the simple expedient of using the vibration of an improperly operating machine to actuate circuit breaking means for circuits supplying power to the driving means of the machine.

While a preferred embodiment of the invention has been described and shown, it is understood that changes and variations may be made without departing from the spirit and scope of the invention as defined in the appended claims.

I claim:

1. In a strand twister comprising a spindle, means for mounting the spindle comprising a resiliently supported non-rotatable bearing-member for the spindle which converts gyratory movement of the spindle into oscillations of the member, electrical driving means for the spindle, and a circuit for supplying power thereto, the combination therewith of a control device comprising a movable element disposed adjacent to the bearing member to be engaged thereby during excessive oscillations thereof, and means responsive to engagement of the element by the member for interrupting the supply of power to the driving means to initiate stopping thereof.

2. In a strand twister comprising a spindle, means for mounting the spindle comprising a resiliently supported non-rotatable bearing-member for the spindle which converts gyratory movement of the spindle into oscillations of the member, electrical driving means for the spindle, and a circuit for supplying power thereto, the combination therewith of a control device comprising a movable element disposed adjacent to the bearing member to be engaged thereby during excessive oscillations thereof, and means responsive to engagement of the element by the member for opening the circuit.

3. In a strand twister comprising a spindle, means for mounting the spindle comprising a resiliently supported non-rotatable bearing-member for the spindle which converts gyratory movement of the spindle into oscillations of the member, electrical driving means for the spindle, and a circuit for supplying power thereto, the combination therewith of a control device comprising a

movable element disposed adjacent to the member to be engaged thereby during excessive oscillations thereof, circuit opening means in the circuit responsive to a reduction in rotation of the spindle below a predetermined speed, and means responsive to engagement of the element by the number for reversing the circuit with respect to the driving means.

4. In a two-for-one strand twister comprising a spindle, means for mounting the spindle comprising a resiliently supported non-rotatable bearing-member for the spindle which converts gyratory movement of the spindle into oscillations of the member, electrical driving means for the spindle, and a circuit for supplying power thereto, the combination therewith of a control device comprising a movable element disposed adjacent to the member to be engaged thereby during oscillations thereof which are of greater amplitude than those produced during normal running, starting and stopping, and a circuit opening device in the circuit responsive to engagement of the element by the member.

5. In a two-for-one strand twister comprising a spindle, means for mounting the spindle comprising a resiliently supported non-rotatable bearing-member for the spindle which converts gyratory movement of the spindle into oscillations of the member, a three-phase motor for driving the spindle, and a three-phase circuit for supplying power to the motor, the combination therewith of control apparatus comprising a switch for opening and closing two phases of the circuit, said switch having a lever supporting a pair of movable terminals normally in contact with a pair of fixed terminals connected with the motor, said lever disposed adjacent to the bearing-member so that the lever is engaged and deflected by the member during excessive oscillations thereof to carry the movable terminals out of contact with the stationary terminals to thereby open the circuit to the motor.

6. In a two-for-one strand twister comprising a spindle, means for mounting the spindle comprising a resiliently supported non-rotatable bearing-member for the spindle which converts gyratory movement of the spindle into oscillations of the member, a three-phase motor for driving the spindle, and a three-phase circuit for supplying power to the motor, the combination therewith of control apparatus comprising a double-throw switch having a pair of movable terminals connected with two phases of a supply circuit, a pair of stationary terminals connected with two terminals of the motor, lever means for supporting the movable terminals and disposed adjacent to the bearing-member so as to be engaged thereby during excessive oscillations thereof, means urging the lever means to hold the movable terminals in contact with the set of stationary terminals in the absence of an oppositely directed force on the lever means, and a second pair of stationary terminals in the switch connected with the terminals of the motor and arranged to be engaged by the movable terminals and to reverse the current to the terminals of the motor when movement of the lever means carries the movable terminals out of contact with the first-named pair of stationary terminals and into contact with the last-named pair.

7. In a two-for-one strand twister comprising a spindle, means for mounting the spindle comprising a resiliently supported non-rotatable bearing-member for the spindle which converts gyratory movement of the spindle into oscillations

8. tions of the member, a three-phase motor for driving the spindle, and a three-phase circuit for supplying power to the motor, the combination therewith of control apparatus comprising a double-pole double-throw trip switch with the movable terminals thereof connected to two phases of a supply circuit, said movable terminals being normally in contact with a pair of stationary terminals connected with the motor during normal operation of the machine, lever means connected with the movable terminals of the switch and disposed adjacent to the bearing member so as to be engaged thereby and to actuate the switch during excessive oscillations of the member whereby the switch is tripped and the members are moved out of engagement with said pair of stationary terminals into engagement with a second pair of stationary terminals, a double-pole delay-relay switch connected with the second-named pair of stationary terminals, a solenoid coil for actuating the delay-relay double-pole switch, a circuit for energizing the coil connected with one of the second-named pair of stationary terminals of the double-throw switch, said coil circuit being closed by engagement of the movable terminals with the second-named stationary pair, said delay-relay switch being connected to reverse the current with respect to the current direction for normal operation, and a reset means for the double-throw switch.

8. In a strand twister comprising a spindle, means for mounting the spindle comprising a resiliently supported non-rotatable bearing-member for the spindle which converts gyratory movement of the spindle into oscillations of the member, a three-phase motor for driving the spindle, and a three-phase circuit for supplying power to the motor, the combination therewith of control apparatus comprising a double-pole double-throw switch having movable terminals connected to two phases of the circuit, a pair of connectors between one pair of stationary terminals of the switch and the motor, a second pair of connectors connecting the other pair of stationary switch terminals and the motor in reverse order, lever means connected with the movable terminals of the switch and disposed adjacent to the bearing-member so as to be engaged thereby and to actuate the switch during excessive oscillations of the member whereby the switch is tripped and the movable members are moved out of engagement with the first-named stationary terminals and into connection with the second-named stationary terminals, a double-pole delay-relay switch in the second set of conductors, a solenoid coil for actuating the delay-relay switch, a circuit for energizing the coil connected to one of the second-named set of terminals of the double-throw switch, said coil circuit being closed by engagement of the movable set and the second-named stationary set of terminals of the double-throw switch, and a reset means for the double-throw switch.

9. In a strand twister comprising a spindle, means for mounting the spindle comprising a resiliently supported non-rotatable bearing-member for the spindle which converts gyratory movement of the spindle into oscillations of the member, a three-phase motor for driving the spindle, and a three-phase circuit for supplying power to the motor, the combination therewith of control apparatus comprising a double-pole double-throw trip switch having movable terminals connected to two phases of the circuit, a set of connectors

between one set of stationary terminals of the switch and the motor, another set of connectors between the other set of stationary terminals of the switch for reversing the flow of current to the motor, a centrifugal switch positioned and connected to open the circuits carried by the second-named set of conductors, said centrifugal switch being maintained in closed position by centrifugal force developed at rotative speeds of the motor above a predetermined minimum, and a lever for supporting and moving the movable terminals of the double-throw switch and disposed adjacent to the bearing-member so as to be engaged thereby during excessive oscillation thereof thereby actuating the tripping mechanism of the switch to carry the movable terminals out of contact with the first-named set of stationary terminals and into contact with the second-named set.

10. In a two-for-one strand twister comprising a spindle, means for mounting the spindle comprising a resiliently supported non-rotatable bearing-member for the spindle which converts gyroscopic movement of the spindle into oscillations of the member, a three-phase motor for driving the spindle, and a three-phase circuit for supplying power to the motor, the combination therewith of control apparatus comprising a unit comprising a plurality of units of single-pole switches secured to a stationary portion of the twister of which one group of normally closed switches are located in the lines of the circuit and a second group of normally opened switches are placed in other lines for reversing the flow of

current to the motor, flexible means secured within the unit and extending at a close clearance with respect to the bearing-member so as to be engaged by the member during excessive oscillation thereof, said flexible means having a portion which engages and actuates the switches when the flexible means is deflected by engagement therewith of the bearing-member.

11. In a two-for-one strand twister having a control apparatus as in claim 10 wherein the switches which are normally closed for the transmission of power during normal operation are spaced with respect to the lever and with respect to the switches for transmitting reversed currents to the motor so that the first-named switches are actuated by engagement of the lever before it actuates the last-named switches.

12. In a twister having control apparatus as in claim 10 wherein the lever is shaped so that when deflected it first opens the switches in the lines for transmitting power during normal operation before closing the switches in the power-reversing lines.
